(57) **CLAIM**

The ornamental design for a virtual reality headset, as shown and described.

DESCRIPTION

FIG. 1 is a first perspective view of a virtual reality headset; FIG. 2 is a second perspective view thereof; FIG. 3 is a front view thereof; FIG. 4 is a rear view thereof; FIG. 5 is a left side view thereof; FIG. 6 is a right side view thereof; FIG. 7 is a top view thereof; and, FIG. 8 is a bottom view thereof.

The design which is claimed is shown in solid lines in the drawings. The broken lines shown in the drawings depict portions of the ultrasonic diagnostic system, and form no part of the claimed design.
